UNITED STATES PATENT OFFICE.

MIJO GRGIČEVIC, OF AKRON, OHIO, ASSIGNOR OF ONE-HALF TO MIKE MARKOVICH, OF AKRON, OHIO.

DESIGN FOR A HEAD ORNAMENT.

Application filed January 9, 1922. Serial No. 119. Term of patent 7 years.

To all whom it may concern:

Be it known that I, Mijo Grgičević, a citizen of Jugo-Slavia, residing at Akron, in the county of Summit and State of Ohio, have invented a new, original, and ornamental Design for a Head Ornament, of which the following is a specification, reference being had to the accompanying drawing, forming part thereof.

The figure is a view in perspective, of a head ornament, showing my new design.

I claim:

The ornamental design for a head ornament, as shown.

MIJO GRGIČEVIC.
